(57) **CLAIM**

The ornamental design for an electronic atomization device, as shown and described.

DESCRIPTION

FIG. 1 is a front perspective View of the electronic atomization device;

FIG. 2 is a front View thereof;

FIG. 3 is a rear View thereof;

FIG. 4 is a right side View thereof;

FIG. 5 is a left side View thereof;

FIG. 6 is a top side View thereof; and,

FIG. 7 is a bottom View thereof.

The broken lines in the drawings depict portions of the electronic atomization device that form no part of the claimed design.
